RING IMPALING PUZZLE

William B. Wilbur, 1516 6th St. N., Arlington, Va.

Filed July 12, 1961, Ser. No. 65,894

Term of patent 14 years

(Cl. D34—15)

FIG. 1 is a front elevation of the puzzle showing my new design;

FIG. 2 is a plan view of FIG. 1; and

FIG. 3 is a vertical sectional view along line 3—3 of FIG. 2.

My design comprises a semi-spherical body of plastic material with a circular base having a flat bottom. A post of substantial diameter extends upwardly from an eccentric point of said base into said body and is curved laterally in a direction parallel to the base. The free end of the post is adapted to have impaled thereon a plurality of rings within said body, the post and rings being clearly visible through the plastic dome of said body.

I claim:

The ornamental design for a ring impaling puzzle, as shown and described.
